GENERATOR FOR PRODUCING A
COMBUSTIBLE OIL GAS

Willem Jan van Heeckeren, Gerard Jan Hubertus Vermeer, and Johan Leonard Baartman, Eindhoven, Netherlands, assignors to Hartford National Bank and Trust Company, Hartford, Conn., as trustee.

Application May 20, 1946, Serial No. 670,965
In the Netherlands November 1, 1945

3. Claims. (Cl. 48—212)

1

It is known that by heating liquid combustible fuels, vapours can be made from these fuels. As far as these fuels have a final boiling point of less than 300° to 350° C. this vaporisation may take place without chemical alterations occurring in the fuel. If, however, the final boiling point exceeds the said limit cracking occurs as a rule. In this case long molecules are transformed into shorter molecules, but at the same time a solid residue comes off. Consequently, the use of an oil-gas from a fuel having a final boiling point above 300° to 350° C. entails that the devices, in which the vapour is produced, have to be cleaned from time to time. Furthermore, such devices have the drawback that the oil-vapours produced cannot be cooled without condensation, in other words no permanent oil gas is produced. In the conventional devices (gas generators) for the production of permanent oil-gases air is supplied to this end during vaporisation. This leads inter alia to partial oxidation of the oil-gas, but only a small fraction of the calorific value of the gas is set free. In this way it is possible to produce a permanent gas. However, all of the conventional devices have the drawback that either the formation of cracking residues is not prevented or no steps are taken to make the cracking residues formed inoffensive.

The present invention has for its object to improve oil-gas generators, as a result of which they do not exhibit the said drawback or only to such a degree that no trouble is experienced during operation.

In the generator according to the invention, with respect to the production of a combustible permanent oil-gas, the oil and the air are brought in counter-current, in intimate contact with each other, and by supplying heat from without the parts of the generator, where substantially only the heavier oil fractions are present, are kept at a temperature having such a value that the solid parts of the fuel ultimately left or formed here out of the fuel are at least for the greater part converted, by oxidation, into gaseous compounds.

By using opposite directions of flow for the fuel and the combustion air in the generator according to the invention the easily evaporating fractions, after vaporisation, are carried first with the air-current in a direction opposite to their initial direction and, as the case may be, locally oxidised. The remaining heavier fuel fractions, which are still liquid, keep moving in a direction opposite to that of the air-current in the generator and steadily meet air which is richer in oxygen than the air met before. The

heavier fractions, which do not evaporate in the air-current and, in generators having the conventional construction, would give rise to the formation of solid unburnt residues, finally find their way to the part of the generator according to the invention where, owing to the supply of heat from without, such a temperature prevails that these residues, due to this high temperature are converted in situ as much as possible into gaseous compounds by oxidation. The advantage of this combustion due to the supply of heat from without over a construction in which the heat required for the combustion of these fractions is completely derived from the process taking place in the generator, consists in that in the generator according to the invention a short measure of combustion air is sufficient, so that the gas produced in the generator is a rich gas. Experiments made by us have shown that in the generator according to the invention a supply of air in the generator amounting, for instance, of from 5 to 10% of the air which is necessary for complete combustion of the gas produced in the generator, is sufficient. In addition, the generator according to the invention is suited to be combined with a burner.

The supply of heat to the generator from without may take place in various ways. Thus, for instance, the air supplied to the generator may be heated prior to its entering the generator, which preferably takes place by means of the flue gases of the burner which is fed with the gas coming from the generator. As an alternative the generator itself may be heated at the location of the heavier oil fractions. According to another embodiment of the invention it is advisable that at the location of the heavier oil fractions the generator should be given a thick wall, or this part should be made from a material having a high thermal conductivity. In the case of the generator part having a thick wall at the location of the heavier oil fractions, it is advisable to feed the air to the generator through a certain number of narrow apertures in this thick-walled part, since in this way the air, which may be cold as the case may be, is very strongly heated.

According to the invention it is advisable as a rule to give the generator part, where the fuel and the air are in counter-current, a vertical position, the fuel inlet pipe emptying in the upper part of the generator part and being cooled to avoid the deposit of carbon.

In order that the invention may be clearly understood and readily carried into effect, it

will now be described more fully with reference to the accompanying drawing given by way of example, in which several forms of construction of the generator according to the invention are represented diagrammatically.

Fig. 1 represents a generator substantially consisting of a vessel 1 having a comparatively narrow neck 2, and air-inlet duct 3, a fuel-supply duct 4 and an outlet duct 5 for the gas produced. In this form of construction the bottom 6 of the vessel 1 has a thick wall. The operation of this generator is as follows. The fuel spouts from the supply duct 4, as indicated in dotted lines. In the neck 2 this liquid fuel meets the air entering the generator through the duct 3 via the narrow apertures 7 in the wall of the generator. This air is preheated, for instance, by the flue gases of the burner (not represented) which is fed with the gas from the generator. Owing to the presence of this preheated air the lighter fractions evaporate from the fuel in the neck 2, and are partly oxidized, as the case may be, by the rising air-current and carried off through the gas duct 5. The heavier fractions, on the contrary, do not evaporate directly; penetrate further into the generator and, after acquiring the required temperature, they will evaporate and, as the case may be, be partly oxidized; together with the air they will rise in the generator and be carried off through the duct 5. The heavier fractions reach the bottom 6 which, as shown by arrows 8, is heated from without. The drops of heated fuel which are present in the bottom part of the generator and will consequently consist of the heavier oil fractions as a rule, appear to keep floating spheroidally above the bottom, and owing to the presence of air very rich in oxygen the vapours formed at this moment, usually cracking products, are entirely or partly oxidized in air rich in oxygen. Ultimately a solid residue substantially consisting of carbon is left on the bottom 6 which, in the course of time, is converted by oxidation into gaseous products due to the circulation of air in this part of the generator. Consequently, the said solid residues entirely disappear due to oxidation. It is desirable to supply the combustion air tangentially to the generator, which is apparently contributive to a suitable mixture of the combustion air and the hydrocarbons.

The generator is preferably designed in such a manner that the whirl of air ensuing in the bottom part of the generator extends eccentrically with respect to the location where the liquid drops on the bottom. In this way the liquid drops are steadily kept moving. As a rule the bottom 6 will have a temperature above 450° C., preferably above 600° C. to ensure the desired effect. Of course, the choice of the temperature depends on the kind of fuel.

The construction of the generator shown in Fig. 2 substantially corresponds to that shown in Fig. 1 but for the difference that vessel 10 with the narrowing neck 11 has a conical bottom 12. To promote the whirling of air the apertures 13 for the inlet of air are located tangentially and directed to the slanting part of the conical bottom. Owing to the projecting edge 14 a kind of whirling chamber is formed at the bottom of the vessel 10, which highly promotes a suitable mixture of fuel and air. Furthermore, in this construction, as also appears from the drawing, the air-inlet ducts 13 are provided in the thick-walled part of the vessel 10. On passing the apertures 13 the air having room temperature, which

is fed through the pipe 15, is heated to, say, 500° C. The air derives heat from the wall of the vessel 10. In fact, as is indicated diagrammatically by arrows 16, the bottom 12 of this vessel is kept at a high temperature. The capacity of this generator exceeds that of the generator shown in Fig. 9. Therefore, the fuel supply duct 17 is designed in such a manner as to spray the liquid fuel in several downwardly directed jets.

An additional advantage of the thick-walled bottom of these generators consists in that the strongly heated bottom is not appreciably cooled by the cold fuel drops reaching the bottom. By giving the generator the shape of a vessel having a narrow or narrowing neck the risk is avoided of spattering fuel drops finding their way into the outlet duct for the gas.

Fig. 3 represents another form of construction of the generator according to the invention, which principally corresponds to the forms of construction shown in Figs. 1 and 2, but for the difference that this generator is more particularly gas-tight in regard to the gasification of kinds of ash-containing oils. The generator comprises an hourglass-shaped housing 20, an air-inlet duct 21, a gas-outlet duct 22, a fuel supply duct 23 and a thick-walled bottom 24. At the bottom the housing 20 is connected to a vessel 25. Between the inner side of the wall of the housing 20 and the vessel 25 on the one hand and the outer edge of the thick-walled bottom 24 on the other hand is provided a narrow slit 27. In the case of a fuel leaving an ash-residue being used in the generator, this residue, due to the air from the air supply duct 21 which enters the housing 20 through the apertures 26 for the inlet of air and initiates a whirl in this housing, will be blown from the bottom 24 over the slightly upstanding edge thereof and will find its way through the annular slit 27 into the vessel 25 which has to be emptied from time to time. The space below the thick-walled bottom 24 contains a device (not represented) to heat the bottom 24 to the required temperature.

Another form of construction of the generator according to the invention is shown in Fig. 4. In this case the generator 30 is shaped as a funnel to which air is supplied through the duct 32 and fuel through the duct 33. Consequently, the fuel and the air are in counter-current in the generator, as indicated by arrows and in dotted lines. The combustible gas is withdrawn from the generator through the duct 34. The funnel-shaped part of the generator is heated on the exterior, as indicated by arrows 35, thus creating the conditions for gasification of the fuels without residue.

At the bottom of the funnel 30 is provided a certain quantity of small particles 31 (globules, grit or the like) which are steadily stirred by the air entering through the duct 32. If unburnt residues should deposit on these particles the residues, as soon as the particles in question, due to stirring by the air at a given moment, such to the bottom of the funnel 31, contact with the fresh air, which is preheated at a temperature of about 500°, and pass over into gaseous compounds. Similarly to Fig. 3 the liquid particles and the air particles in the funnel are in counter-current with each other.

In the construction of the generator shown in Figs. 5 and 6 a rotary member 43 is provided between the mouth of the fuel-supply duct 41 and the air-supply duct 42 and the solid residues from

the fuels will deposit on this member. This member is rotatable in the direction of the arrow. It is impelled, for instance, by the solid fuel residues unilaterally depositing on this member, as a result of which the right-hand part of the member 43 becomes heavier than the left-hand part thereof, or by impelling it from without. In this case the solid fuel residues come automatically from surroundings poor in oxygen to a surrounding which is richer in oxygen, where these residues will consequently be burnt. In the construction shown in Fig. 6 the widened portion 44 of the generator housing, in which the left-hand part of the member 43 is rotatable, contains a scraper 45 by which any solid fuel parts left on the member 43 are removed therefrom. These particles drop and find their way into the bottom part of the generator where, due to the prevailing high temperature and the fresh air they are burnt, as a result of the external heating, without leaving any residues, or are at least converted into gaseous compounds.

What we claim is:

1. A method of generating combustible gas from liquid hydrocarbons containing differing oil fractions comprising the steps of introducing such liquid hydrocarbons downwardly and freely into an unobstructed generating space, introducing externally heated air upwardly into said generating space in a confined substantially straight stream to freely flow directly counter-current to said freely falling liquid hydrocarbons for intimately mixing with and vaporizing the lighter fractions of said liquid hydrocarbons, permitting the unvaporized heavier fractions of said liquid hydrocarbons to continue downwardly and freely until a heating area is reached, heating said heating area to a temperature above that of said heated air for oxidizing and vaporizing said heavier oil fractions therein, and conducting a mixture of said vaporized lighter fractions of said hydrocarbons, said vaporized heavier fractions of said hydrocarbons, and said heated air from the top region of said generating space.

2. A generator for the production of combustible gas from liquid hydrocarbons containing differing oil fractions comprising a vessel having side walls, means for introducing liquid hydrocarbons into said vessel at a point substantially at the top of said vessel, said means being so located with regard to said side walls of said vessel that liquid hydrocarbons issuing from said means will normally fall freely for the depth of said vessel before finally impinging on the bottom of said vessel, said bottom of said vessel being substantially thick, a plurality of narrow apertures in said vessel near the bottom thereof and directed towards said bottom, means for conducting air from outside said vessel through said apertures and into the bottom area of said vessel to impinge on said bottom, means for heating said bottom of said vessel, and gas outlet means at the top of said vessel whereby the air passing through said apertures is heated and then freely flows directly countercurrent to the liquid hydro-

carbons introduced into said vessel for intimate mixing with and vaporization of the lighter oil fractions of the liquid hydrocarbons, the combustible gases thus produced pass off through said gas outlet means, and the heavier unvaporized oil fractions impinge on the heated bottom of said vessel where such oil fractions are ultimately oxidized into vapor to finally pass off through said gas outlet means.

3. A generator for the production of combustible gas from liquid hydrocarbons containing differing oil fractions comprising a vessel having a raised bottom above its true bottom, means for introducing liquid hydrocarbons into said vessel at a point substantially at the top of said vessel, said means being so located with regard to the walls of said vessel that liquid hydrocarbons issuing from said means will normally fall freely for the depth of said vessel before impinging on said raised bottom in said vessel, said raised bottom having upstanding edges, passage means laterally beyond said upstanding edges communicating the vessel space above said raised bottom with a vessel space below said raised bottom, means for introducing air into said vessel in the region just above said raised bottom, means for heating the underside of said raised bottom of said vessel, and gas outlet means at the top of said vessel whereby the air introduced into said vessel flows counter-current to the liquid hydrocarbons introduced into said vessel for intimate mixing with and vaporization of the lighter oil fractions of the liquid hydrocarbons, the combustible gases thus produced pass off through said gas outlet means, the heavier unvaporized oil fractions impinge on the heated lower portion of said vessel where such oil fractions collect and are ultimately oxidized into vapor to finally pass off through said gas outlet means, and any ash residue collecting on said raised bottom is blown past said upstanding edges by the air introduced into said vessel and into said passageway means to collect in said vessel space below said raised bottom.
